UNITED STATES PATENT OFFICE.

GERSON IGERSHEIMER, OF FRANKFORT-ON-THE-MAIN, GERMANY.

COIN-FREED APPARATUS.

SPECIFICATION forming part of Letters Patent No. 640,202, dated January 2, 1900.

Application filed April 6, 1898. Serial No. 676,702. (No model.)

To all whom it may concern:

Be it known that I, GERSON IGERSHEIMER, a subject of the Emperor of Germany, and a resident of Frankfort-on-the-Main, Germany, 5 have invented certain new and useful Improvements in Coin-Freed Apparatus, of which the following is a specification.

This invention relates to improvements in coin-controlled apparatus for securing various articles, such as clothing or bicycles, in place.

The object of the invention is to provide a device that may be operated either upon the insertion of a coin therein or the manipulation 15 of an operating-key in the hands of authorized persons.

The invention has for its further object to produce a device of this nature which may be unlocked by the manipulation of a second 20 key and also the provision of means whereby the unlocking-key is retained in the device while it is unlocked and released when the device is locked.

A further object is to provide means for retaining the operating-key in the device while it is locked and for releasing it when the device is unlocked.

To accomplish these ends, there are provided two normally-independent cams, with 30 their dependent mechanism, a locking-arm for securing the articles in place, and a bolt for engagement with said cams to make them coercive and thereupon permit the locking-arm to be operated. These cams are also 35 adapted to be connected by a coin to accomplish the same result. In combination with these parts are others, to be hereinafter described, which coöperate to produce the other objects of the invention.

40 Of the accompanying drawings, Figure 1 is a side view of the apparatus. Fig. 2 is a front side view of the device with the cover removed, showing the position of the mechanism when the device is unlocked. Fig. 3 is a similar view, the device being locked. Fig. 4 is an elevation of the coin-chute-engaging disk. Fig. 5 is an elevation of the engaging stop-disk. Fig. 6 is an elevation of the connection bearing-disk. Fig. 7 is an elevation 45 of the bevel-arm. Fig. 8 is a front side view of a part of the auxiliary bolt, and Figs. 9 and

10 are plan views of opposite faces of the bolt. Fig. 11 is a detail view of a special key:

The cover of the device is shown at A, and B denotes the base-plate. An angular plate 55 5 is secured to the base B, and its upright part has a circular perforation to serve as a bearing-support for a rock-shaft 11, which is journaled at its other end in a similarly-perforated angular plate 6, which is also secured 60 to the base B. The rock-shaft carries at one end a manually-operable locking-arm E. Secured to the rock-shaft 11, between the supports 5 and 6, is a cam F, (shown in detail in Fig. 4,) provided with a hub 12, which carries 65 a slot 13. The cam F is also formed with a circular perforation 14, a shoulder 15, and an engaging notch 16. A coil-spring 17 surrounds the rock-shaft 11, having its ends secured in the support 5 and rigidly secured to 70 cam F and forcing the locking-arm E to remain normally at the extreme limit of its open position. A second cam G is mounted upon the rock-shaft 11, but not secured thereto, contiguous to the cam F. Cams F and G do not 75 normally coact, but are adapted to be connected for simultaneous operation. The cam G, as shown in Fig. 5, has a series of formations which register and coact with corresponding parts of the cam F, viz: Coin-slot 18 registers with slot 13, engaging notch 19 registers with notch 16, stop 20 coacts with the shoulder 15, and perforation 21 registers with perforation 14 of the cam F. The cam G is also provided with a square shoulder 43. 85

An angular plate 7 is secured to the base B, having its ends bent up to form bearing-supports 8 and 9 for a locking-bar K. The locking-bar is formed with a lug 31 at one end, adapted to bear along the periphery of the cam 80 G and to engage in the notches 19 and 16 of the cams G and F when the apparatus is locked. A coil-spring 33 is mounted on the locking-bar K, between the supports 8 and 9, bearing with one end against the support 9 and 90 with the other against a collar 34, mounted on the locking-bar and held by a dowel-pin 35. The spring 33 maintains the locking-bar K with a constant pressure upon the periphery of the cam G. Inclined grooves 36 are milled 95 out on both sides of the locking-bar K at a convenient part of its length, Figs. 8, 9, and 100

10, and on one side is left a shoulder 37 for retaining the key in the device.

An angular retaining-plate L (shown in detail in Fig. 7) is secured to the locking-bar K 5 and is beveled sharply at two of its edges 38.

Angular plates 22 and 23 are secured to the base B, and their uprights are adapted to serve as supports for a key-operated reciprocating rod H. This rod H is formed with a 10 cylindrical portion 24 and a rectangular portion 25, the latter serving as a bearing-shoulder for a coil-spring 26, which surrounds the cylindrical portion 24 and bears with its other end against the supporting-plate 23. Inclined grooves 27 are milled out from both sides of the rectangular part 25, and a shoulder 28 is left for retaining the key. This construction is similar to that upon the locking-bar K and is shown in detail in Figs. 8, 9, 15 and 10.

A rotatable cam I (shown in detail in Fig. 6) is mounted on the end of the reciprocating rod H, and this cam carries a projecting pin-bolt J, which is always engaged in the perforation 21 of the cam G and is adapted on the reciprocation of the rod H to pass through the perforation 14 of the cam F to adapt the cams F and G for coaction. Owing to the constant engagement of the pin-bolt J in the 20 perforation 21 the cams I and G will always rotate simultaneously. The cam I, as shown in Fig. 6, is cut away to form two sides 30, the edges of which are beveled sharply to adapt them for engagement with the beveled 25 edges 38 of the retaining-plate L.

In Fig. 11 is shown a form of key C which may be used to operate the reciprocating rod H or the locking-bar K, or both. As shown, it is a metal plate formed with a slot 39, lug 40, and handle-piece 41. When this key is inserted in a key-slot and pressed down, its lower edges come in contact with the ends of the inclined grooves 27 or 36, imparting longitudinal movement to the member in which 45 the grooves are formed. The lug 40 passes under the shoulder 28 or 37, and when the longitudinal movement of the grooved member has carried the open portion of the groove beyond the key-slot the key cannot be withdrawn.

The operation of the device is as follows: When it is desired to control its operation by a coin, the coin is inserted in the coin-slot of the cover A, whence it falls into the slot 13 55 of the cam F, coming to rest only when it lies partly within said slot and partly in the coin-slot 18 of the cam G. The cams are now co-active. When it is desired to control the operation by the bolt, the pin-bolt J is caused 60 to proceed from its normal position within the perforation 21 of the cam G until it is engaged also in the registering perforation 14 of the cam F. The cams are now also co-active. When the key C is inserted and 65 pressed downward, it is forced upon the inclined grooves 27 of the reciprocating rod H, causing the latter to be moved in the direc-

tion of the cam G against the tension of the spring 26. The open groove 27^a now passes beyond the lug 40, and the key C is retained by the shoulder 28 against removal. By this movement of the rod H the cam I also is brought into engagement with the retaining-plate L, the beveled edge 30 of the cam acting with the beveled edge 38 of the plate to force the latter to one side against the pressure of the coil-spring 33 on the bar K. The cam is permitted by this movement of the plate to pass beyond the latter, when immediately the plate, under pressure of the spring 33, resumes its original position and prevents the reciprocation of the rod under pressure of the coil-spring 26. Furthermore, with this movement of the rod H the pin-bolt J is pushed through the perforation 14 of the cam F, thus locking the cams F and G together, making them coactive. The position of the parts at this point is illustrated in Fig. 3. The cam I can never be rotated independently of the cam G, because the pin-bolt J is 90 always engaged in the perforation 21 of the cam G, and the latter is prevented from rotation independent of the cam F, because its stop 20 engages with the shoulder 15 on cam G and its shoulder 43 engages with the lug 31 on the locking-bar K. The locking-arm E is next turned against the pressure of spring 17 until it is engaged with the garment-support K'. In this movement the cam F is 95 rotated with the rock-shaft 11, forcing with it the cam G by means of the shoulder 15 and stop 20, and hence when the pin-bolt has 100 been forced into engagement with the perforation 14 the cam F forces also the cam I to rotate with it. The cam G bears with its 105 periphery against the lug 31 of the bar K against the pressure of spring 33 until the lug 31 engages in the notches 16 and 19 of the cams F and G, and the parts are locked, and an unlocking-key coöperating with the 110 inclined grooves 36 and 37 may be removed.

When it is desired to unlock the apparatus, the unlocking-key is pressed upon the inclined grooves 36, forcing the lug 31 out of engagement with the notches 16 and 19. The 115 unlocking-key will now be retained, and the locking-arm E being released will be forced back by the spring 17 until brought to rest by the engagement of the shoulder 43 of the cam G with the lug 31. Reverse operations 120 take place with the remaining parts, and if the pin-bolt has been used to connect the cams it rotates the cam I back to its original position. When the cam I approaches the end of its rotation, its beveled edges 30 come 125 again in contact with the beveled edges 38 of the retaining-plate L. When the locking-bar K is moved by the cam G, it carries with it the retaining-plate L, the beveled edges of 130 which slide along the beveled edges of the cam I until only their knife-edges are in contact, when the cam I is released, and under pressure of the coil-spring 26 the reciprocating rod H, carrying the cam I, returns to its

original position. By this movement the pin-bolt J is withdrawn from engagement with the cam F, the key C is released from the shoulder 28, and the parts are again in position to be operated either by the key or a coin.

The invention can be modified in unessential respects to make it applicable to any coin-controlled apparatus, and I do not limit myself to the described structure.

10. What I claim, and desire to secure by Letters Patent of the United States, is—

15. 1. In a coin-controlled apparatus, the combination with coin-controlled operating means, of independently-constructed key-controlled means adapted to coact with said operating means to enable the apparatus to be positively operated without the interposition of a coin, substantially as described.

20. 2. In a coin-controlled retaining device, the combination with means for retaining articles in place, of means for locking said retaining means adapted to be made operable upon the insertion of a coin or other article, and means for causing said locking means to become operable without the insertion of a coin, substantially as set forth.

25. 3. In a coin-controlled retaining device, the combination with means for retaining articles in place, of coin-controlled means for locking said securing means, and key-operable means for rendering said locking means operable without the insertion of a coin, substantially as described.

30. 4. In a coin-controlled locking device, the combination with coin-controlled locking means normally inoperable, of key-operable means for rendering said locking means operable without the insertion of a coin, and key-operable means for unlocking said device, substantially as described.

35. 5. In a coin-controlled locking device, the combination with coin-controlled locking means normally inoperable, of key-controlled means for making said locking means operable, means for retaining the key in the device when it is locked and for releasing the key when the device is unlocked, means for unlocking the device by another key and for releasing the latter key when the device is locked and retaining it when the device is unlocked, substantially as described.

40. 6. In a coin-controlled locking device, the combination with normally-inoperable coin-controlled locking means, of key-operable means adapted to coact with said locking means to render the same operable without the insertion of a coin, and means for retaining the key for said means in the device when it is locked, substantially as described.

45. 7. In a coin-controlled locking device, the combination with normally-inoperable coin-controlled locking means, of key-operable means adapted to coact with said locking means to render the same operable without the insertion of a coin, and key-controlled means for unlocking the device, substantially as described.

50. 8. In a coin-controlled locking device, the combination with normally-inoperable coin-controlled locking means, of key-operable means adapted to coact with said locking means to render the same operable without the insertion of a coin, key-operable means for unlocking said device and retaining the unlocking key when the device is unlocked, substantially as described.

55. 9. In a coin-controlled locking device, the combination with manually-operable locking means, normally inoperable, and adapted to be made operable by the engagement with it of a coin or bolt, of a key-operable bolt for engaging with said locking means, and means for retaining the key in the device when the device is locked, substantially as described.

60. 10. In a coin-controlled locking device, the combination with coin-controlled manually-operable locking means, normally inoperable, but adapted to be made operable by the engagement therein of a coin or of a bolt, a key-operable bolt for engaging with said locking means; key-operable means for unlocking the device and retaining the key of the last-named means in the device when the device is unlocked, substantially as described.

65. 11. In a coin-controlled apparatus, the combination with operating means comprising two normally non-coactive parts adapted to be connected for coöperation by a coin or bolt, of a key-operable device for forcing a bolt into engagement with said parts, substantially as described.

70. 12. In a coin-controlled apparatus, the combination with operating means comprising two normally non-coactive parts having mutually registering perforations for the reception of a coin or of a bolt, of a key-operable bolt for engagement with said parts, substantially as described.

75. 13. In a coin-controlled apparatus, the combination with coin-controlled operating means comprising a rock-shaft, a cam rigidly secured to said rock-shaft and formed with a slot, a second cam loosely mounted on said rock-shaft independently of said cam and formed with a coin-slot, both cams having registering perforations, of a key-operable bolt adapted to engage in said perforations, substantially as described.

80. 14. In a coin-controlled apparatus, the combination with coin-controlled operating means comprising two independent cams having registering perforations adapting them to be made coöperative by the insertion of a coin or a bolt, of a key-operable bolt for engagement with said cams, substantially as described.

85. 15. In a coin-controlled securing device, the combination with a manually-operable locking mechanism consisting of a locking-arm and a rock-shaft, of two independent cams mounted on said rock-shaft, only one of said cams being secured to said shaft, said cams being adapted to be connected together by a coin or a bolt, of a locking-bar adapted to en-

gage said cams with one end, a retaining-plate secured to said locking-bar and having beveled faces, a bolt to connect said cams together, a cam carrying said bolt and having 5 its edges beveled for engagement with the beveled edges of said retaining-plate, a key-operable reciprocating rod upon which said bolt-bearing cam is rotatably mounted, inclined surfaces on said reciprocating rod to 10 permit its operation by a key, and a shoulder

on said rod for engaging with the key to retain the key in place after the rod has been operated, substantially as described.

In testimony whereof I have signed my name to this specification in the presence of 15 two subscribing witnesses.

GERSON IGERSHEIMER.
